R. C. RUSSELL

CARD INDEX

Filed Oct. 29, 1924

Inventor

R. C. Russell

By Symon & Bright

Attorneys

UNITED STATES PATENT OFFICE.

ROBERT C. RUSSELL, OF PITTSBURGH, PENNSYLVANIA.

CARD INDEX.

Application filed October 29, 1924. Serial No. 746,637.

To all whom it may concern:

Be it known that I, ROBERT C. RUSSELL, a citizen of the United States, and a resident of Pittsburgh, in the county of Allegheny and State of Pennsylvania, have invented certain new and useful Improvements in Card Indexes; and I do hereby declare the following to be a full, clear, and exact description of the invention, such as will enable others skilled in the art to which it appertains to make and use the same.

This invention relates to improvements in card indexes of the "visible" type and has for its object the provision of index elements which shall be so constructed that they will be properly supported, one by another in uniform spaced relation so as to provide exposed data receiving portions of uniform area throughout the series of index elements and so that all of the index elements shall be retained normally in proper position in a holder but capable of being moved or removed as may be required.

With this and other objects in view, the invention consists in certain novel features as hereinafter set forth and pointed out in the claims.

In the accompanying drawings,—

Figure 1 is a face view showing a card index illustrating my improvements.

Figure 2 is a rear view in perspective of one of the index elements.

Figure 3 is a rear face view showing several index elements, and

Figure 4 is a fragmentary sectional view on the line 4—4 of Figure 1.

The index elements 1 are supported, movably and removably by a holder 2, the latter having shoulders 3 at its respective end portions and provided at its side portions with flanges 4 which overlie portions of the bottom of the holder and provide guide-ways 5 which receive the ends of the cards or index elements 1.

Each index element 1 may be made of cardboard or other suitable flexible material. Each card or element 1 is slit near its respective ends on diagonal convergent lines, forming inwardly projecting, horizontal approximately V-shaped tongues 6 and the

apices of these tongues are preferably rounded as shown at 7. The material of the card between the base portion of the respective tongues is bent rearwardly and upwardly, forming a resilient tongue 8 and an elongated pocket 9. The bend at the juncture of the elongated tongue with the body portion of the card is preferably rounded as indicated at 10 so that said tongue will have sufficient resilience to make such frictional engagement with the face of the body portion of the holder as will retain the index element in proper position in said holder.

In assembling the index elements, the inwardly projecting tongues 6 of one element will be caused to engage and be supported in the pocket 9 formed by the tongues 8 of an adjacent element, and the exposed portions of the several index elements will have uniform areas.

Having fully described my invention what I claim as new and desire to secure by Letters-Patent, is:

1. In a card index, an index element having inwardly projecting tongues near its respective ends and the material between the base portions of said tongues being bent rearwardly and upwardly forming a resilient tongue providing a pocket.

2. In a card index, the combination with a frame having parallel guide-ways, of a plurality of index elements to enter said guideways at end portions of said elements, each index element having inwardly projecting tongues near its respective ends and the material of each index element between the base portions of said tongues being bent rearwardly and upwardly forming an elongated pocket to receive the inwardly projecting tongues of an adjacent index element.

In testimony whereof, I have signed this specification in the presence of two subscribing witnesses.

ROBERT C. RUSSELL.
